UNITED STATES PATENT OFFICE.

FRANK H. HARRIS, OF AUBURNDALE, OHIO.

VEHICLE-WHEEL.

SPECIFICATION forming part of Letters Patent No. 403,346, dated May 14, 1889.

Application filed October 2, 1888. Serial No. 286,948. (No model.)

To all whom it may concern:

Be it known that I, FRANK H. HARRIS, a citizen of the United States, residing at Auburndale, in the county of Lucas and State of Ohio, have invented certain new and useful Improvements in Vehicle-Wheels, of which the following is a specification, reference being had therein to the accompanying drawings.

- 10 This invention relates to a new and useful improvement in vehicle-wheels; and the invention has special reference to that class of vehicle-wheels constructed of metal with wire spokes.
- 15 My invention consists in the peculiar construction of the hub, in combination with the novel means for securing the wire spokes thereto, all as more fully hereinafter described, and set forth in the drawings, in which—
- 20 Figure 1 is a vertical central cross-section of a vehicle-wheel embodying my improved construction. Fig. 2 is a cross-section of a vehicle-hub with my improvement slightly modified. Fig. 3 is a detached perspective 25 of the parts of the hub, as shown in Fig. 2; and Fig. 4 is an enlarged perspective view of the inner end of a wire spoke, as constructed in accordance with my invention.
- A is the hub, B are the wire spokes, and 30 C is a rim, of an iron vehicle-wheel of known construction, except as to devices employed for securing the spokes to the hub and which embody my invention. These consist in flattening the inner ends of the spoke in such 35 manner as to form the wedge-shaped dovetail, as shown at *a* in Fig. 4, in detail, such dovetail being tapered in two planes at right angles to each other and in inverse directions to each other, and may be accomplished by 40 pressing or swaging the ends of the spoke between suitable dies. To secure the spokes thus prepared to the hub, I provide radial spoke-notches *c* of exactly corresponding shape with the ends of the spokes, or only 45 slightly shallower, upon the outer end of the hub, insert the ends of the spokes therein, and clamp them by means of a cap, E, firmly secured to the hub by means which exert a clamping action against the spokes. To this 50 end I provide the hub with a spindle-box, *d*, which projects from the end of the hub, and

which is screw-threaded and engages into a corresponding screw-thread in the cap E. Furthermore, I preferably form an annular recess, *e*, in the inner face of the cap, so that 55 when the cap is secured upon the hub the pressure brought against the spokes is concentrated upon a small portion of the spokes, which are thereby held firmly in place.

Instead of the screw-thread engagement 60 between the thimble-box and the cap, the construction shown in Fig. 2 may be used, wherein the thimble-box is smooth on the outside and fits into the aperture of the cap. By rivet-heading the spindle-box upon the 65 end of the cap it is then firmly secured.

It will be noticed that my spoke-notches are formed entirely in the hub of the wheel and have to be of such shape relatively to the dovetail formed on the inner end of the 70 spokes as to prevent the withdrawal of the spokes, and at the same time to present the outwardly-extended face of the dovetail in proper relation to the clamping-face of the cap to securely clamp the spoke. 75

My construction is applicable to the different styles of wheels—that is, to the wheel constructed as shown in Fig. 1, which is two rows of spokes inclined to the rim, or to the style of wheel shown in Fig. 2, which is provided with only one row of radial spokes. In the former construction both ends of the hub are provided with the means for securing its respective row of spokes, and, if desired, in the construction shown in Fig. 2, the hub A 85 may be provided with a rim corresponding to the rim *h* of the cap. 80

What I claim as my invention is—

1. A vehicle-wheel composed of the hub provided with the radial spoke-notches *c*, tapered, as described, and slightly shallower than the ends of the spokes, the spokes having their inner ends flattened to form a wedge-shaped dovetail, said dovetail being tapered in two planes at right angles to each other 90 and in inverse directions to each other, and the cap E on the spindle of the hub, and having a flat vertical bearing on the flattened portion of the spokes, substantially as shown and described. 95

2. In a vehicle-wheel, the combination, with 100 the wire spokes B of the wheel, of a dovetail,

a, formed on the inner end of the spokes and tapering inversely to each other in two planes at right angles to each other, the hub of the wheel provided upon its end with radial spoke-
5 notches corresponding with the dovetail formed upon the ends of the spokes, or slightly shallower, the cap *E*, provided with an annular recess, *e*, upon its inner face, and the spindle-box on the hub, as the means for se-

curing and clamping the cap to the hub, sub- 10 stantially as described.

In testimony whereof I affix my signature, in presence of two witnesses, this 10th day of September, 1888.

FRANK H. HARRIS.
